SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,355,635.

Specification of Letters Patent.

Patented Oct. 12, 1920.

Application filed December 27, 1918. Serial No. 268,501.

To all whom it may concern:

Be it known that I, SAMUEL B. WILLIAMS, Jr., a citizen of the United States, residing at Brooklyn, in the county of Kings, State 5 of New York, have invented certain new and useful Improvements in Telephone-Exchange Systems, of which the following is a full, clear, concise, and exact description.

This invention relates to an improvement 10 in telephone exchange systems and has particular reference to a semi-mechanical private branch exchange system employing rotary line and selector switches.

An object of the invention is to provide an 15 improved selector switch arranged to serve a plurality of groups of trunks, any one of which may be selected by a directive movement of the brushes of the switch, the terminals of the trunks in certain of said 20 groups being interspersed either periodically or promiscuously and in such a manner as to materially reduce the automatic trunk-hunting operation in the groups necessary before finding an idle trunk in the 25 selected group.

Another object is the provision of a terminal bank for a selector switch wherein 30 certain of the terminals are each allotted for determining the selection of one of a plurality of groups of trunks having connection with other terminals of said bank. In accordance with this arrangement, the 35 brushes of the switch may, during the directive and automatic movements thereof in seizing an idle trunk in the selected group, pass over the terminals allotted for group selection and also terminals of trunks in non-selected groups, the test for an idle trunk in the selected group depending upon 40 the finding of two terminals within the same set simultaneously free from ground.

The inventive idea involved is capable of 45 receiving a variety of expressions, one of which, for the purpose of illustrating the invention, is shown in the accompanying drawings, but it is to be expressly understood that said drawings are employed merely for the purpose of illustrating the invention as a whole and not to define the 50 limits thereof, reference being had to the appended claims for this purpose.

In the drawings, Figures 1 and 2 combined, with Fig. 2 at the right of Fig. 1, 55 illustrate diagrammatically the various circuits of the private branch exchange sys-

tem; Fig. 3 is a diagrammatic view of the trunking arrangement employed in connection with the invention.

In carrying out the invention, switches of the rotary type having contacts arranged 60 in a complete circle are preferably employed for interconnecting the telephone lines. In Fig. 3, wherein the trunking arrangement is disclosed, a subscriber's substation A is shown in association with a line switch B, 65 the brushes of which are caused to move over the terminal bank by the removal of the receiver at substation A and automatically select an idle trunk, whereby the line is extended to a first selector switch C. The 70 multiple bank of this switch consists of a plurality of terminals, certain of which are available for trunks divided into groups. Two of these groups c' and c^2 are available for automatically extending a connection 75 to selector switches D when interconnecting calling and called subscribers within the private branch exchange. The terminals of said groups in the multiple bank of switch C are shown as arranged alternately but 80 it is to be understood that said terminals may be promiscuously interspersed or disposed at random without departing from the spirit and scope of the invention. The multiple of the several banks is such that 85 a different trunk appears as the first trunk in each multiple bank or group of multiple banks. By this arrangement, the selectors will not be required to hunt over all the busy trunks, and the number of busy trunks 90 passed over will be on the average the same when calling through the first group as when calling through the second group. The other two groups of trunks c^3 and c^4 95 may be used in establishing connections to a private branch exchange operator's position and to a central office exchange, respectively. The terminals in the trunks of each of these groups, in contradistinction to the terminals of groups of trunks c' and c^2 , are preferably 100 arranged in the ordinary manner.

In the final selector switch D, three groups of trunks d' , d^2 and d^3 are shown, and depending upon the number of tens impulses transmitted by the sender at substation A 105 in making an automatic connection to a called substation, the brushes of the final selector are stepped around to one of three terminals. The units digits of numbers in the first two groups are selected by the dial 110

impulses, but when a number in the last group is called, a group relay operates on the completion of the impulses for the tens digit, as will appear later, causing the stepping magnet of the final selector to automatically step the brushes around to the last group, and the dialing of the units digit of the number then selects the desired trunk in this group.

10 The operation may be briefly stated as follows: Should a subscriber at substation A desire a connection to the central office exchange, the removal of his receiver will first operate line switch B to seize an idle trunk.

15 The impulse sender is then manipulated to transmit one impulse which will step the brushes of the first selector switch C to the second terminal of the multiple bank and thus select the group of central office trunks c^4 .

20 By this selection the terminals of all the other groups of trunks are rendered non-selectable and the brushes of the switch will be stepped over these terminals and caused to hunt for an idle trunk in the group c^4 , whereupon the connection will be extended to the central office.

25

If it is desired to automatically establish a connection between two subscribers within the private branch exchange, the calling subscriber will, by removing his receiver, seize an idle trunk connected to the line switch, and by operating the sender to transmit two or three impulses, depending upon which of the groups c' or c^2 is to be selected, the brushes of the selector C will be stepped to the corresponding terminal in the selector bank allotted to the particular group, whereupon a trunk-hunting operation will proceed over the terminals of the group of trunks selected.

30 As previously stated in connection with the trunk hunting in group c^4 , the terminals of all the other groups, with the exception of the one in which trunk hunting is now proceeding will likewise be made non-selectable so that should all the trunks in the selected group be busy, the brushes of the selector will travel over the groups of trunks c^3 and c^4 in order that a busy tone will be transmitted to a subscriber at substation A.

35 Upon the seizing of a trunk in either of the two groups c' or c^2 , the line is extended to the final selector switch which is operated, as briefly referred to above, connect the calling and called subscribers.

40 To call the private branch exchange operator, the digit 0 is dialed to send ten impulses after a connection has been extended from the line switch and the brushes of the selector are stepped to the terminal of the bank in association with the groups of trunks c^3 , at which time a trunk-hunting operation would again take place to select an idle trunk leading to the operator's position.

45 Again, as described in connection

with the trunk-hunting operations in other groups, the terminals thereof, in this instance, will be rendered non-selectable in order that trunks therein will not be seized.

The trunking arrangement above described forms the subject-matter claimed in the present application, and the means herein shown and described for establishing the different connections have been disclosed and claimed in a separate application to 70 Samuel B. Williams and Bert G. Dunham, filed on December 27, 1918, and bearing Serial No. 268,468.

It is believed that the invention will now be best understood from a detailed description of the operation in establishing a connection from a calling subscriber to a called subscriber and also to central office and private branch exchange trunks. Upon the removal of the receiver at substation A, in 80 initiating a call, line relay 200 of the line switch B is energized over a circuit from grounded battery, winding of relay 200, back contact and innermost lower armature of cutoff relay 201, substation apparatus, 85 upper armature and back contact of relay 201 to ground. The marginal stepping magnet 202 is then energized over the circuit from grounded battery, winding of said magnet, armature and back contact thereof, 90 front contact and armature of line relay 200 and lowermost brush 203 to ground at the normal terminal thereof, whereupon the brushes of the switch will be stepped to the second set of terminals, the trunks of which 95 lead to one of the first selector switches. Should the selector switch connected to the first test terminal be busy, brush 203 of the line switch B engaging said terminal will be grounded at the back contact of the line relay of the line switch connected to said selector switch, and a circuit will be found for stepping magnet 202 extending from grounded battery, winding of said magnet, 100 armature and back contact thereof, front contact and armature of relay 200, brush 203, armature and back contact of the line relay of said other line switch to ground. Magnet 202 being self-interrupting, will again step the brushes of the line switch 105 over the terminal bank until an idle trunk is found, whereupon a circuit is established from grounded battery, winding of magnet 202, back contact and armature thereof, 110 winding of relay 201 in series with said magnet, brush 204, conductor 304, winding of low resistance relay 307, brush 308 of the selector switch, back contact and innermost right armature of test relay 303, and right armature of relay 301 to ground. Magnet 115 202 being marginal and in series with relay 201, will not operate, but relays 201 and 307 will operate and the former will extend the subscriber's line to the idle selector switch C. Line relay 200 deenergizes and its back 120

contact grounds the test terminal and makes the trunk test busy to all other line switches.

Line relay 309 of the selector switch will 5 energize immediately upon energization of relay 307 due to a circuit extending from grounded battery, right winding of relay 309, armature and front contact of relay 307 to ground. A circuit for relay 309 will be 10 maintained from grounded battery, right winding of relay 309, back contact and innermost lower armature of cutoff relay 310, lower side of the subscriber's line, substation apparatus, upper side of subscriber's 15 line, back contact and upper armature of relay 310, left winding of relay 309, brush 311 and coil 312 to ground. First slow-to-release relay 305 is then energized by a circuit extending from grounded battery, winding 20 of relay 305, and front contact and armature of line relay 309 to ground. Operation of relay 305 establishes a holding circuit for relay 201 extending from grounded battery, winding of magnet 202, armature and 25 contact thereof, winding of relay 201, brush 204, conductor 304 and left armature of relay 305 to ground. A dial tone is furnished by coil 312 to inform the subscriber that he may now operate his sending device. If the 30 subscriber desires to establish a connection to another P. B. X. subscriber, he will now transmit two or three impulses, depending upon which group of trunks c' or c^2 is to be selected for the trunk-hunting operation. 35 Interruption of the circuit of line relay 309 by the sending device causes the armature thereof to vibrate, and upon each retraction a circuit is closed for the stepping magnet 313, extending from grounded battery, winding 40 of magnet 313, winding of slow-to-release relay 301, right armature of slow-to-release relay 305, which remains energized during the line interruptions, back contact and outermost lower armature of cutoff relay 45 310 and back contact of the armature of relay 309 to ground. The brushes of the selector are stepped from their normal terminals in accordance with the number of impulses sent, and upon deenergization of 50 relay 301 at the termination of the transmission of impulses, one of the two group relays 314 and 315 is energized. Assuming that the two impulses were sent to select the group of trunks c' , group relay 314 will be 55 energized over a circuit extending from grounded battery, winding of relay 314, brush 308 which now rests upon the third terminal in its row, back contact and innermost right-hand armature of test relay 303 60 and right armature of relay 301 to ground. Relay 314 in attracting its right armature, energizes test relay 303 over a circuit extending from grounded battery, right winding of said relay, lowermost brush 316, the 65 third terminal in the row associated with said brush, front contact and right armature of relay 314 to ground. After test relay 303 is energized, relay 314 is held up until an idle trunk is found, over a circuit extending from grounded battery, winding of relay 314, left 70 armature and front contact thereof and left armature of slow-to-release relay 305 to ground. Stepping magnet 313 is now operated over a circuit extending from grounded battery, winding of said magnet, armature 75 and back contact thereof, front contact and outer left armature of relay 303, front contact and right armature of relay 314 to ground. It is to be noted that the continued energization of relay 314 has removed the 80 ground at its right armature from the terminals of the selected group c' traversed by the brush 316, but that as long as the test brush 317 of the selector is moving over busy trunks, test relay 303 is held up over a circuit 85 from grounded battery, left winding of relay 303, front contact and inner left armature thereof, test brush 317 to ground at the busy final selector. It is therefore apparent that relay 303 will not release until brushes 90 316 and 317 engage two terminals simultaneously free from ground, and consequently stepping magnet 313 continues to operate until an idle trunk is found. During the energization of test relay 303, a ground is 95 placed upon the conductor 302 except when relay 301 is energized, and this ground provides an additional guarding potential which will prevent seizure of the selector by another line switch when the latter is hunting for an idle trunk. When brushes 316 and 317 simultaneously engage two terminals free from ground, test relay 303 will retract its armatures and break the circuit for 100 stepping magnet 313, and brushes of the selector will come to rest upon the selected terminals. Cutoff relay 310 is immediately energized by the circuit extending from grounded battery, winding of relay 310, back contact and outer right armature of 105 test relay 303, brush 308, back contact and inner right armature of test relay 303, and back contact and armature of relay 301 to ground, and the line is thus extended to the final selector switch D. Upon the operation 110 of cutoff relay 310, line relay 309 and slow-to-release relay 305 deenergize but the upper and inner lower armatures of relay 310 being of the make-before-break type, the connection is cut through and ground is found 115 at the final selector for relay 201 and group relay 314 before the ground at relay 305 is removed, and said relays thus remain energized. 120 If all of the trunks in the group are found 125 to be busy, test relay 303 remains energized until the brushes of the switch have been stepped onto the last set of terminals, at which time brush 317, no longer finding ground, will cause relay 303 to deenergize, 130

and upon the release of relay 303, cutoff relay 310 is energized over a circuit extending from grounded battery, winding of relay 310, back contact and outer right armature of relay 303, brush 317, inner left-hand armature and back contact of relay 303, normal contact and left-hand armature of relay 301, left-hand armature and alternate contact of relay 305 to ground. Upon energization of cutoff relay 310, a busy tone is placed on the calling line by a circuit extending from grounded battery, right winding of line relay 309, brush 318, lower side of the telephone line, substation apparatus A, upper side of the telephone line, brush 319 and coil 325 of busy tone device B Z to ground. Through this circuit, relay 309 is held energized until the receiver at substation A is replaced upon its hook. Line relay 309 then releases whereupon slow-to-release relay 305 will become deenergized. This latter relay opens a circuit for relay 310 at its left-hand front contact above described. The release of relay 310 closes a circuit from ground, armature and back contact of relay 309, lower armature and back contact of relay 310, right-hand armature and back contact of relay 305, brush 316, right-hand winding of relay 303 to grounded battery. The energization of relay 303 closes a circuit for stepping magnet 313 from grounded battery, the winding, armature and back contact of said magnet, left-hand outer front contact and armature of relay 303, left-hand back contact and armature of relay 305 to ground. The stepping magnet 313 will become energized and step the switch to normal position at which position relay 303 will be deenergized and the circuit is then restored to its normal condition. The line switch is restored to normal in a manner to later appear.

Assuming now that an idle trunk was found, upon the energization of cutoff relay 310, line relay 400 of the final selector switch D becomes energized over a circuit extending from grounded battery, right winding of relay 400, lower side of the telephone line, substation apparatus A, upper side of the telephone line and left winding of relay 400 to ground. In attracting its armature, relay 400 closes the circuit for slow-to-release relay 401 which extends from grounded battery, winding of relay 401, front contact and armature of relay 400 to ground. Relay 401 attracts its left armature and establishes the ground previously referred to in connection with the holding circuit for relay 201 and group relay 314. When relay 401 is energized, relay 402 is also energized over a circuit extending from grounded battery, winding of relay 402, brush 403 in its normal position, conductor 404 to ground at the left armature of relay 401. If the desired number is within the groups of trunks d' or

d^2 of the final selector switch D, shown in Fig. 3, the impulse-sending device at substation A is operated to transmit either one or nine impulses, depending in which group the trunk-selecting operation is to take place. Assuming that the called number is in group d' , the sending device is operated to transmit one impulse, and in response thereto the armature of relay 400 will be retracted and close a circuit for the stepping magnet 405 extending from grounded battery, winding of magnet 405, front contact and inner left armature of relay 402, winding of slow-to-release relay 406, back contact and left armature of relay 407, right armature of slow-to-release relay 401 and back contact and armature of relay 400 to ground. The brushes of the switch are thereby stepped onto the second set of terminals. Upon energization of relay 406 in response to the impulse transmitted a circuit was closed for relay 408 extending from grounded battery, winding of said relay and right armature of relay 406 to ground, and said relay 408 locked up through its outermost lower armature and front contact, armature and back contact of relay 409 and left armature of slow-to-release relay 401 to ground. The group of trunks d' has now been selected, and at the termination of the impulse, slow-to-release relay 406 deenergizes, but relay 402 remains energized over a circuit extending from grounded battery, winding of relay 402, brush 403, conductor 404 and left armature of slow-to-release relay 401 to ground. Upon transmitting the units impulses to select the desired line in the group d' , stepping magnet 405 is again operated over the previously described circuit to step the brushes of the switch. It is to be noted that as soon as the brush 403 leaves the second terminal, ground will no longer be found for relay 402 at the left armature of slow-to-release relay 401, but relay 402 will remain energized over a circuit extending from grounded battery, winding of said relay, left armature and back contact of group relay 410 and left armature of slow-to-release relay 406 to ground. Relay 406 remains energized during the transmission of impulses. Stepping magnet 405 will thus continue to operate in accordance with the impulses transmitted until the brushes have been stepped upon the desired set of terminals. If the line selected is found to be busy, relay 402 will find ground at the left armature of slow-to-release relay 406 until the same becomes deenergized at the termination of the impulses, whereupon the circuit for relay 402 will be extended from the back contact of the left armature of relay 406, through relay 407, inner right armature and back contact thereof, front contact and outer left armature of relay 402, brush 411 to ground at the busy terminal of 130

the called line. Relay 407 will lock up through its inner right armature to ground at the left armature of relay 401. Attraction of the outer right armature of relay 5 407 furnishes a busy tone to the calling line extending from grounded battery, right winding of line relay 400, lower side of the subscriber's line substation apparatus A, upper side of subscriber's line, outer right armature of relay 407 and coil B Z to ground.

Should the called line be idle, relay 402 releases at the end of the impulses, since upon deenergization of relay 406, the ground at the left armature of the latter 15 relay will be removed. Upon the release of relay 402, relay 412 becomes energized over a circuit extending from grounded battery, winding of relay 412, right armature and back contact of relay 402, back contact and 20 innermost right armature of group relay 410, brush 413 and back contact and right armature of slow-to-release relay 406 to ground. Energization of relay 412 extends the line to the selected terminals and closes 25 a circuit extending from the ringing current generator 414, right winding of relay 409, front contact and inner lower armature of relay 408, lower armature and front contact of relay 412, ringer apparatus at the 30 called substation E, front contact and upper armature of relay 412 and inner upper armature of relay 408 to ground. Ringing current is thus applied to the line and is also induced into the secondary winding of relay 409 for the purpose of furnishing a 35 ringing tone to the calling station, the circuit for this ringing tone extending from grounded battery, left winding of relay 415, lower side of the telephone line, substation apparatus A, upper side of the telephone line, right winding of relay 415 and left winding of relay 409 to ground. Relay 409 is marginal and will not attract its armature 40 as long as the resistance of the substation 45 bell is in its circuit, but when the receiver at the called substation E is removed, said relay will become energized and break the circuit for relay 408 which extended through the armature and back contact of 50 said relay 409. Relay 408, in releasing, disconnects the ringing current and closes the talking circuit at the innermost upper and lower armatures and back contacts, and conversation may proceed.

55 If the trunk for the called line had been located in group d^2 , it would have been necessary to transmit nine impulses to the final selector, to step the brushes thereof onto the tenth terminal shown in the bank 60 of the selector D in Fig. 3 and in so stepping the brushes, the operation would be precisely the same as that set forth above. It should be noted that no line numbered 91 65 appears, since the terminal which should have been allotted for line No. 91 is, in

stead, allotted for the selection of group d^3 . Should the tens digit of the called number be 0, the brushes are stepped around as previously described until they engage the eleventh terminal shown in Fig. 3, whereupon, 70 as soon as relay 406 releases at the end of the impulses, group relay 410 is energized by a circuit extending from grounded battery, winding of relay 410, conductor 416, brush 413, back contact and armature of relay 406 75 to ground. The operation of relay 410 energizes relay 402 over a circuit extending from grounded battery, winding of relay 402, left armature and front contact of relay 410 to ground. Energization of relay 80 410 also closes a circuit for stepping magnet 405 extending from grounded battery, winding of magnet 405, armature and back contact thereof, outermost right armature and front contact of relay 410, conductor 416, 85 brush 413, back contact and armature of relay 406 to ground. Magnet 405 is now self-interrupting and operates to automatically step the brushes of the switch. Upon the first step of said brushes, relay 410 locks up 90 over a circuit extending from grounded battery, winding of relay 410, front contact and innermost right armature thereof, conductor 417, brush 413, back contact and armature of relay 406 to ground. The stepping 95 operation of the brushes continues until brush 413 reaches the terminal having no connection to the conductor 417, whereupon said brushes come to rest on this set of terminals. Relay 410 releases, but relay 402 100 continues to be energized over a circuit from grounded battery, winding of relay 402, brush 403, conductor 404 and left armature of slow-to-release relay 401 to ground. In response to the units impulses, the brushes 105 are again stepped around in the trunk selecting movement in group d^3 in the same manner as previously described for calling a number in group d' .

Should the subscriber, after initiating a 110 call, hang up his receiver before an idle trunk leading to the selector switch has been seized, it will be apparent that the line switch will continue to hunt for the idle trunk, and upon finding it, cutoff relay 201 115 will be energized as previously described. Relay 307, being in series with relay 201, also energizes, and at its front contact, closes a circuit for line relay 309, which in attracting its armature, energizes slow-to- 120 release relay 305, thus grounding conductor 304, leading from cutoff relay 201, at the left armature of relay 305, instead of at the back contact and right armature of relay 301 and thereby shunting relay 307. Release of this 125 relay deenergizes line relay 309, since the line circuit has been broken by replacing the receiver, and armature of relay 309 closes the circuit of stepping magnet 313 extending over the previously traced circuit, 130

and the brushes are stepped onto the second set of terminals. In response to the continued deenergization of line relay 309, relay 305 becomes deenergized and after an interval, relay 301 follows. Group relay 320 is then energized over a circuit extending from grounded battery, winding of relay 320, brush 308, back contact and inner right armature of test relay 303, back contact and right armature of slow-to-release relay 301 to ground. The right armature of group relay 320 puts ground on the set of test terminals associated therewith, and test relay 303 is consequently energized by the circuit extending from grounded battery, right winding of relay 303, brush 316, front contact and right armature of relay 320 to ground. Energization of relay 303 closes a circuit for stepping magnet 313 from grounded battery, winding of magnet 313, armature and back contact thereof, front contact and outer left armature of relay 303, back contact and left armature of slow-to-release relay 305 to ground, relay 305 having become deenergized upon the release of line relay 309. The brushes are now stepped to the next set of terminals and this action takes place each time the brush 316 engages one of the terminals which is connected to ground at the right armature of group relay 320. When engaging the test terminals of the different groups c' , c^2 and c^3 , brush 316 finds ground for test relay 303 at the back contacts and armatures of the respective group relays. When relay 320 is energized, ground for the group of terminals c^1 extends from the armature and back contact of relay 309, outer lower armature and back contact of relay 310, right armature and back contact of relay 305, outermost and middle left armatures and front contacts of relay 320 to said terminals. Stepping magnet 313 continues to operate until the last set of terminals is reached, whereupon the switch is stepped to normal, as previously described. It is to be understood that the terminals indicated by dotted lines over which brush 316 moves are connected to the other terminals of the respective groups in the same manner as shown in full lines. Upon the shunting of relay 307 as previously described, relays 309 and 305 will release, and the holding circuit for relay 201 will be broken at the left armature of relay 305. Stepping magnet 202 will then operate to step the switch B to normal over the circuit extending from grounded battery, winding of magnet 202, armature and back contact thereof, lowermost armature and back contact of relay 201 and brush 205 to ground at the armature and back contact of line relay 200.

At the termination of a conversation, in the event that a connection has been estab-

lished between the calling and called substations, the hanging up of the receiver at substation A releases line relay 400 of the final selector switch D which also causes slow-to-release relay 401 to deenergize. Relay 410 now energizes over the circuit extending from grounded battery, winding of relay 410, brush 418, back contact and right armature of slow-to-release relay 401, back contact and armature of relay 400 to ground. Energization of relay 410 breaks, at its innermost right armature and back contact, the circuit for cutoff relay 412 causing this relay to release. Stepping magnet 405 is now operated over the circuit extending from grounded battery, winding of magnet 405, armature and back contact thereof, outermost right armature and front contact of relay 410, brush 418, back contact and right armature of slow-to-release relay 401, back contact and armature of relay 400 to ground, and stepping magnet 405 continues to operate until the switch is stepped to its normal position where the circuits for said magnet and relay 410 are broken.

In order to prevent the selector switch D from being seized during the return of the switch to its normal position, it being understood that the busy ground has been removed by the deenergization of slow-to-release relay 401, a ground is provided at the middle right armature and front contact of relay 410.

The removal of ground at relay 401 releases group relay 314 of selector switch C and places ground on all trunks of the selected group associated with said relay and thereby energizes test relay 303 over a circuit extending from grounded battery, right winding of relay 303, brush 316, terminal of the selected trunk, back contact and right armature of relay 314 to ground. Test relay 303, pulling up, opens at its right armature and back contact, the circuit for cutoff relay 310 and closes the circuit for stepping magnet 313 extending from grounded battery, winding of magnet 313, armature and back contact thereof, front contact and outer left armature of relay 303, back contact and left armature of relay 305 to ground, and stepping magnet 313 continues to operate as long as brush 316 engages a terminal which finds ground at the right armature of relay 314, and will also operate upon each engagement of brush 316 with the test terminals associated with group relays 315, 320 and 321, which are deenergized. If the brushes have selected an idle trunk in groups c' and c^2 before reaching the terminal to which they would be stepped when selecting group of trunks c^3 , relay 303, in passing over said terminal, will be energized by the circuit extending from grounded battery, right winding of relay 303, brush 316, conductor 322, back contact and left armature of relay 130

305 to ground, and stepping magnet 313 will thus again step the brushes onto the next set of terminals.

Line switch B is also returned to normal by the removal of ground at left armature of slow-to-release relay 401 which causes the release of cutoff relay 201, this relay having been held energized by the circuit extending from grounded battery, winding 10 of stepping magnet 202, armature and back contact thereof, winding of relay 201, brush 204, conductor 304, left armature and back contact of relay 301, back contact and inner left armature of relay 303, brush 317 and 15 left armature of relay 401 to ground. The release of relay 201 energizes stepping magnet 202 over a circuit extending from grounded battery, winding of magnet 202, armature and back contact thereof, lowermost armature and back contact of relay 201 and brush 205 to ground at the armature and back contact of line relay 200. Stepping magnet 202 continues to operate until the brushes thereof engage the normal terminals, whereupon the operating circuit of said magnet will be broken and the switch will come to rest.

If it is desired to establish a connection to a central office, subscriber at substation 30 A, by removing his receiver, will operate line switch B to select an idle trunk leading to one of the first selectors, and upon transmitting a single impulse, the brushes of said selector will be stepped, as previously described, onto the second set of terminals and thus select the group of trunks c^4 for the trunk hunting operation which automatically takes place in the same manner as described in connection with the extension of 40 a call through group of trunks c' , group relay 320, in this instance, becoming energized.

Should the service of substation A be restricted a conductor 207 is employed to connect the middle lower armature of cutoff relay 201 of the line switch with brush 206, so that if an attempt is made to call the central office from this station, energization of cutoff relay 201 will apply said ground to the 50 central office trunks and cause the same to test busy, said ground extending through the brush 206, conductor 323, front contact and middle left-armature of group relay 320, which has become energized, to the terminals of the central office trunks. Stepping magnet 313 will therefore continue to operate until the last set of terminals is reached, whereupon test relay 303 will be energized over a circuit extending from 60 grounded battery, right winding of relay 303, brush 316, the last test terminal, outermost left armature and front contact of relay 320, conductor 323, brush 206 and middle lower armature and front contact of relay 65 201 to ground, thus causing the stepping

magnet to again operate and return the switch to normal position. Line switch B, however, remains in its actuated position as long as the receiver is off the switchhook and the subscriber may again manipulate 70 his dial to call the private branch exchange operator.

To establish a connection to the private branch exchange operator's position, the sending device at substation A is actuated, 75 after the seizure of an idle trunk by the line switch B, to transmit ten impulses to step the brushes onto the eleventh set of terminals, whereupon group of trunks c^3 will be selected for the trunk hunting operation, and 80 in this case group relay 321 will be energized to remove ground from the terminals of the private branch exchange trunks over which test brush 316 passes and one of the trunks will be seized in the same manner as previously described. 85

What is claimed is:

1. In a telephone system, a trunking arrangement for switches including a bank and groups of trunks terminating in said 90 bank and having their terminals interspersed, other terminals of the bank being allotted for group selection.

2. In a telephone system, a trunking arrangement for switches including a bank, 95 and groups of trunks terminating in said bank and having their terminals interspersed, whereby terminals of one group of trunks are passed over in selecting a trunk in another group, other terminals of said 100 bank being allotted for group selection.

3. In a telephone system, a trunking arrangement for switches including a bank, and groups of trunks terminating in said bank and having their terminals interspersed, whereby terminals of one group of trunks are passed over in selecting a trunk in another group, other terminals of said bank being allotted for group selection, the latter terminals being initially passed over 110 in selecting a group of trunks. 105

4. In a telephone system, a trunking arrangement including a terminal bank, groups of trunks connected to terminals of said bank and having their terminals interspersed, and other groups of trunks connected to other terminals of said bank, certain other terminals of the bank being allotted for group selection. 115

5. In a telephone system, a trunking arrangement including a terminal bank, groups of trunks connected to terminals of said bank and having their terminals interspersed, and other groups of trunks connected to other terminals of said bank, certain 125 other terminals of the bank being allotted for group selection, one of the latter terminals being arranged between terminals of the first named groups.

6. In a telephone system, a trunking ar- 130

rangement including a terminal bank, groups of trunks connected to terminals of said bank and having their terminals interspersed, and other groups of trunks connect-
5 ed to other terminals of said bank, certain other terminals of the bank being allotted for group selection and being initially passed over in selecting one of said groups.

7. In a telephone system, a trunking ar-
10 rangement including a terminal bank, groups of trunks connected to terminals of said bank and having their terminals interspersed, and other groups of trunks connect-
15 ed to other terminals of said bank, certain other terminals of the bank being allotted for group selection and being initially passed over in selecting one of the first named groups.

8. In a telephone system, a trunking ar-
20 rangement including a terminal bank, groups of trunks connected to terminals of said bank and having their terminals interspersed, and other groups of trunks connect-
ed to other terminals of said bank, certain

other terminals of the bank being allotted 25 for group selection and being initially passed over in selecting one of the last named groups.

9. In a telephone system, a trunking ar-
20 rangement including a terminal bank, groups of trunks connected to terminals of said bank and having their terminals interspersed, and other groups of trunks connect-
35 ed to other terminals of said bank, certain other terminals of the bank being allot-
30 ted for group selection, one of the latter terminals being arranged between terminals of the first named groups, others of said cer-
tain terminals and the terminals of the first named groups being passed over when se-
40 lecting the group of trunks allotted to the terminal which is arranged between terminals of said first named groups.

In witness whereof I hereunto subscribe my name this 23rd day of December, A. D. 45 1918.

SAMUEL B. WILLIAMS, JR.
